UNITED STATES PATENT OFFICE.

WILLIAM D. DICKSON, OF PEORIA, ILLINOIS.

SYSTEM FOR HEATING AND VENTILATING HOUSES.

SPECIFICATION forming part of Letters Patent No. 611,359, dated September 27, 1898.

Application filed April 30, 1892. Serial No. 431,229. (No model.)

To all whom it may concern:

Be it known that I, WILLIAM D. DICKSON, a citizen of the United States, residing at Peoria, in the county of Peoria and State of Illinois, have invented certain new and useful Improvements in Systems for Heating and Ventilating Houses; and I do hereby declare that the following is a full, clear, and exact description of the invention, which will enable others skilled in the art to which it appertains to make and use the same.

My invention relates to certain new and useful improvements in systems for heating and ventilating buildings.

More particularly my invention relates to a system for heating and ventilating in which the natural laws controlling the air are utilized in connection with certain mechanical parts and constructions to obtain the desired results.

Heretofore systems for heating and ventilating have been separate and distinct—that is, the heating system for a building was a separate and distinct means employed, performing the one particular function through the means provided, and the ventilating system or the means provided for ventilating the same building, if any were provided at all, was entirely separate and distinct from the heating system and in no way dependent thereon or auxiliary thereto in the performing of its particular function. In my system I have made the ventilating system auxiliary to and dependent upon the heating system—that is, I provide a heating system and so arrange the means employed that it will facilitate the ventilation—that is, the heat from the heating system by the proper communication with the ventilating system will cause or produce a condition in the ventilating system that will render it operative for the purpose designed.

My invention consists, essentially, in the arranging of heat and ventilating flues, relatively of the same proportion, side by side, of a heat source for supplying the necessary heat to the heat-flues of the system and also to the ventilating-flues by radiation through the dividing-partitions or through openings in said partitions by direct communication from the heat source with the vent-flues to cause a rarefaction of air in the ventilating-

flues, whereby an upward current will be established therein, so that when the system is applied practically, with a heat-flue communicating with an apartment of a building, it will supply the necessary heat for the said compartment, and a ventilating-flue arranged side by side with the heat-flue and opening out of the said apartment and extending upwardly, communicating with the open air at a point outside the building, will receive a sufficient amount of heat to rarefy the air therein and cause the necessary draft.

In addition to the above-specified parts of my invention I have provided a coil box or boxes for containing steam-coils that I prefer to use in connection with my system, which said coil-box has certain details of construction adapting it for the particular purpose that will hereinafter be particularly explained. Also I provide a room for receiving the necessary supply of fresh air to be heated either by the coils I provide or by other suitable means to provide the heat for the heat-flues, and a duct communicating with and drawing air from the attic of a building, and of certain other details of construction hereinafter more particularly pointed out in the specification and claims and indicated by reference to the drawings.

That my invention may be more fully understood reference is had to the accompanying drawings, in which—

Figure 1 is a perspective view showing my system for heating and ventilating as applied to a building, only so much of the building being shown as is deemed necessary to illustrate the manner of applying the system for practical use in connection with a building. Fig. 2 is a detail view showing the application of a coil-box to a heat-flue and showing the coil-box as being substantially a part of the flue or a continuation of the same or a formation thereof, adapting it to receive the steam-coils and also shown in connection therewith. Fig. 3 is a front view of the coil-box proper. Fig. 4 is a sectional view showing a portion of the base of a heat-flue and a vent-flue and showing the relative adjustment and arrangement with relation to each other and the application of the coil-box to the base of the flues and the actual construction of the coil-box, minus the steam-coil designed to be

contained therein. Fig. 5 shows a vertical section through the flues and a portion of the building in which they are located. Fig. 6 is a section through the line X X of Fig. 5 and 5 shows particularly the arrangement of the flues. Fig. 7 is a section showing in detail the general character of the dividing-partitions and also showing an opening or communicating passage-way from a heat-flue into a vent-flue and also showing a deflecting-plate in a heat-flue purposed to direct the heat therefrom and into an adjacent compartment, which deflector may also be made to serve as a dividing-partition, if desired, in the heat-flue, separating it from a portion above which is a continuation of the same flue, but being used as 10 a ventilating-flue. Fig. 8 is a detail view showing a front elevation of heat and vent flues and the manner of combining the same 15 to adapt them for use in connection with a first-floor compartment and a compartment on the second floor of a building, and they may be used, as shown in solid lines, entirely 20 separate, or they may be combined, as shown 25 in dotted lines in connection with the solid lines, to heat and ventilate two compartments, one above the other. Fig. 9 is also a detail view showing the manner of arranging the 30 heat and vent flues when used for heating 35 compartments all located upon the same floor. Fig. 10 is a detail view showing the arrangement of the flues and the application of the same for heating three sets of compartments, one above the other, making six compartments in all, as is necessary in heating a three-story building.

In the drawings, A B C show the floors of a building.

D is a stack or battery of flues, which may be 40 constructed in the manner shown in the drawings—viz., a rectangular wall may be built up and may be divided by thick partitions, as a b, to form the separate flues E and E', which may be adapted for use one as a smoke-flue 45 and the other for a dry-closet flue, as I would use them in constructing buildings, and the stack may further be divided by means of the thin partitions c c c c c, which may be of any suitable material, as sheet metal or brick, or 50 the flues may be built up in any suitable manner, so long as they are arranged so that portions of heating and ventilating flues overlap each other through a portion of their height.

The series of flues formed by means of the 55 partitions, as above noted, are designated by R, S, T, U, V, W, X, E, and E', which said flues are built up side by side, and, as shown in the drawings, the adjacent flues have partitions in common, although the arrangement 60 of the flues may be somewhat modified, so that the principle of operation desired to be employed may be carried out by a slightly-modified means substantially equivalent to the same shown in the drawings.

65 Referring to Fig. 5, it will be noted, as has been previously stated in the short description of the said figure, that a vertical section

is taken through the flues, and in the said figure R' is a vent-flue and may be constructed in connection with a main battery of flues 70 and is designed in this particular application to ventilate a hallway in a building. S' is a heat-flue open at its base and connects with an apartment through the register-opening S² in the wall, a portion of which is shown in 75 the drawings and designated by S³, the said register-opening being located, preferably, at a point near to the top of the room, and the flue may be divided horizontally by means of the partition S⁴, if desired, or a curved deflector may be placed in the flue in such position with relation to the register-opening as to properly deflect the heat toward said register-opening.

Referring to Fig. 7, a deflector of the kind 85 mentioned is indicated by S⁵. S⁶ is an opening in the wall or common partition between adjacent heat and vent flues. S⁷ is a hood over the said opening projecting outwardly within the heat-flue. This is only one of many means 90 that may be employed for injecting a small quantity of heat into a ventilating-flue with a view of rarefying the air therein. I might use ducts of any suitable character leading from the source of heat to the vent-flues, as 95 will readily be understood, and I have only shown this particular means in order that I may indicate my desire to inject hot air into the ventilating-flues to rarefy the air therein, but desire to employ any suitable means for 100 accomplishing this object. S⁸ is a box placed at the bottom of flue S' and is designed to contain steam-coils, the particular and detailed construction of said box being shown in Figs. 2, 3, and 4 of the drawings, and by 105 reference to said figures it will be seen that the said box may be simply a continuation of the flue from its normal base, or a box of any suitable material—as, for instance, sheet metal—may be attached thereto. I prefer to 110 use the sheet-metal box, and in its construction is made wider than the heat-flue proper and of sufficient width to overlap the adjacent ventilating-flue one-half of its width. The box is also made to extend outwardly 115 and forward from the flues some little distance in order that room may be provided for a sufficient number of coils to be placed therein to provide a proper amount of heating capacity.

Referring to Fig. 4 particularly, we will assume that the portions of flues therein shown are the flues shown in the other figures and designated by R' and S'. S⁸ is the coil-box proper, which has an opening in its top portion matching with the opening in the base of the flues S', the base of vent-flue R' being closed. The coil-box is designed to contain coils S⁹, which may be arranged in any suitable manner therein. S¹⁰ is an opening in the 120 coil-box, which is designed to be located above the surface of the coils within the coil-box. S¹¹ is a damper hinged to the lower edge of the said opening. S¹² is a chain connected

with said damper and carried upwardly and leading to the room which is heated by the heat-flue S' and in such position that it may be reached and operated conveniently, the 5 damper S¹¹ being so adjusted with relation to the coils that when lowered it will cover the same completely and when raised to its maximum height will close the opening S¹⁰ in the side of the coil-box. The manipulation of 10 the damper facilitates in the regulation of the heat-supply to the flue S', and the particular and detailed operation of the same will hereinafter be more particularly described in the short description of the operation of the system 15 hereinafter given. S¹³ is an opening in the bottom of the coil-box which is provided to admit air into the box to pass between and circulate around the coils and when so heated to be conducted through the heat-flue S' to 20 the compartment with which said flue communicates. S¹⁴ is a slide supported in suitable clips at the bottom of the box and designed to regulate the supply of air to the coils. It may be adjusted to open the coil-box to the full size of the opening therein or 25 to partially open the same, or it may close the opening entirely, as may be desired. The circumstances requiring said manipulation will hereinafter be more particularly specified. 30

Referring to Fig. 5, T' is the heat-flue, open at its base and communicating with an apartment through the register-opening T² in the wall of the room and a section of which is designated by T³, the flue being divided at the 35 floor-line by means of the cross-partition T⁴, and a deflector, the same as used in flue S', may be placed therein for properly deflecting the air. T⁵ is a ventilating-flue which, together with the portion of the flue designated 40 by T', forms the complete flue T. T⁶ is a register-opening in the wall of a compartment, a portion of which is designated by T⁷, this register-opening being preferably located 45 near to the floor-line. The register-opening S² is designed to admit the air from the heat-flue S' into a compartment, and the register-opening T⁸ is designed to indicate the portion 50 of the dividing-partition S that is common to heat-flue S' and the vent-flue T⁵, and in the operation the radiation of the heat there-through will rarefy the air in the ventilating-flue, causing a draft upwardly therein. T⁹ refers to a coil-box which is exactly the same in 55 detailed construction as coil-box S⁸ and opens into and supplies heat to heat-flues T'. U is a ventilating-flue, as has been previously stated, the same being closed at its base. U' is a register-opening in the wall of a room adjacent thereto, a portion of the wall being indicated by U². The register-opening T² from the heat-flue T' is designed to conduct hot air into a given room and the register-opening U² into the ventilating-flue U is designed to 60 conduct the vitiated air therefrom. As shown in the drawings, the said heating and ventilating flues, provided with the register-open- 65

ings S², T², and U', are arranged to supply and provide the necessary heat and to ventilate two rooms located in front of said flues 70 or adjacent thereto. V' is a heat-flue open at its base and communicating with an apartment through register-opening V² in the wall of the room. V³ is a partition in the said flue above the said register-opening, and a deflecting-plate may also be used in addition to the said partition or in place of it to divide the flues and to properly deflect the air to the register-opening V², or the one or the other of the said parts may be omitted, as may 75 be desired, the purpose being that the flues shall be so divided as to properly conduct the hot air into a given compartment and the vitiated air therefrom. V⁴ is a coil-box communicating with the base of the flue V' to 80 supply heat thereto by means of the hot air from the steam-coils therein. W' is also a hot-air flue provided with the register-opening W² into a room. W³ is a partition above the said register-opening dividing the flue, 85 and a deflector may be provided therein in addition to the said dividing-partition, or the one or the other may be used alone without the other. W⁶ is a coil-box for supplying heat to the said flue. W⁴ is the upper portion 90 of the complete flue W and serves in this construction as a ventilating-flue. W⁵ is a register-opening therein which communicates with a compartment, the ventilating-flue being open at the top for communicating with the open air. X is a ventilating-flue closed 95 at its base and provided with a register-opening X' therein which communicates with an apartment. The register-openings V², W², W³, and X' are designed to communicate with 100 two compartments, one above the other, and to facilitate the heating and ventilating of the same. 105

A short description of the operation of the flues as arranged and shown in Fig. 5 may 110 be given, as follows: Heat rising in heat-flue S' will supply the heat for a given compartment and by radiation through the partition T⁸ will rarefy the air in ventilating-flue T⁵, causing a draft therein which will extract 115 from the said compartment the vitiated air, and it also happens in the arrangement of the flues that the radiation from the said heat-flue will rarefy the air in ventilating-flue R', causing a draft therein which will 120 extract the vitiated atmosphere from an adjacent hallway. Heat from flue T' will supply the necessary hot air for a given compartment and by radiation through the partition T¹³ will rarefy the air in the ventilating-flue 125 U, which communicates with the register-opening U², and will cause the vitiated atmosphere to be extracted from said compartment. V' is a heat-flue that supplies heat to a given compartment and by radiation through partition V⁷ will rarefy the air in the vent-flue W², which communicates with a compartment through register-opening W⁵, which 130 will cause the vitiated air in the compartment 135

to be extracted therefrom. X' is a heat-flue which communicates with a compartment. X is a ventilating-flue. X^2 is a partition between the two flues. The heat in the heat-flue 5 by radiation through the partition will rarefy the air in the said vent-flue, causing a draft therein which will cause the vitiated air in the compartment with which said vent-flue communicates to be extracted therefrom. F 10 is a room at the base of the combined flues and within which the coil-boxes at the base of the said flues are located, which said room is designed to receive a supply of fresh air, and in this drawing I have shown the supply 15 of fresh air as coming from the upper portion of the building, the shaft for that purpose being designated by G , which opens into the said room through the opening G' . G^2 is a trap-door which may be placed over 20 the top of the said shaft. G^3 is a cord which may be provided for operating the said door to raise it or to lower it, the said cord working over the pulley G^4 . The fresh air may be supplied by any suitable means—by a 25 duct opening directly from the side of the building into said room or in any other suitable manner—the means herein shown being only one of many that may be employed.

In Fig. 8 of the drawings I have shown in 30 detail the arrangement of two flues J K and L M side by side, having register-openings J' K' and L' M' , (one flue for heat and one for vent,) and showing portions of each flue overlapping and having a common partition. 35 I have shown this arrangement of flues both for the first floor of the building and for the second floor of the building and show how they may be constructed the one independent of the other—that is, how they may be arranged 40 for heating one room on one floor and how they may be arranged for heating one room on the second floor—and I have shown the same combined—that is, I have indicated by dotted lines how the second-floor heat and 45 vent may be combined with the first-floor heat and vent—to simplify construction. This figure shows fully my preferred manner of arranging the flues to derive heat from the heat-flues by radiation to rarefy the air in 50 the vent-flue.

In Fig. 9 I have shown the arrangement of my flues to facilitate the heating of rooms which are all located upon one floor or the manner of adapting the system for use in connection with one-story buildings, the figure 55 showing the arrangement of the flues to accommodate the heating of rooms on opposite sides thereof, N and P being heat-flues having the register-openings N' and P' , and O and Q refer to vent-flues having register-openings O' and Q' , and as the rooms are multiplied in a building all that is necessary to do is to supply new batteries of flues, the same as shown in this figure, to accommodate 60 the heating of rooms on the opposite sides of flues so arranged.

In Fig. 10 I have shown an arrangement of

my flues and ventilating on the first, second, and third floors of a building, these rooms being arranged in pairs on either side of said flues, thus making six rooms in all. In applying the system for heating and ventilating six rooms it is necessary for me to add two extra flues for heat and two coil-boxes, and I obtain the necessary ventilating-flues 7 by the continuation of the other heat-flues of the system. H represents one of the heat-flues, H' the register-opening therein, and H^2 the coil-box therefor. I also represents the heat-flue for the third story, I' the register-opening therein, and I^2 a coil-box for supplying heat to the flue. H^3 is a ventilating-flue, and H^4 is a register-opening therein. I^3 is a ventilating-flue, and I^4 is a register-opening therein. 8

In the drawings and specification I have shown the system adapted for use in connection with one, two, and three story buildings. I have shown substantially the manner in which I prefer to arrange the flues; but I 9 may arrange them differently—that is, I may combine the flues differently in order to accommodate them for a particular use or to peculiar constructions of buildings that would render a modification of the plan herein 9 shown necessary. In fact, many modifications may be made of the detailed construction of the separate banks of flues; but I desire always to maintain the arrangement I have shown in the drawings—that is, their arrangement side by side and their separation by a common wall or dividing-partition, as it renders the construction simple.

I might separate the flues entirely—that is, a heat-flue and a vent-flue—thus destroying 10 the common dividing-wall, and communicate heat to the ventilating-flue by means of a pipe leading from the coil-box or from any suitable source; but the construction I have shown I deem the simplest and the most practical way of applying the principle I desire to employ—that is, the heating of the air in the ventilating-flue to cause a draft therein to facilitate in proper ventilation.

It will be noted in the drawings that in heating a two-story building four coil-boxes are employed, which is the number that I can most conveniently employ in connection with a battery of flues, and it will be noted that these coil-boxes are arranged side by side 11 and that each one extends over the base of the heat-flue and overlaps a portion of the next flue. This arrangement enables me to gain the required space below the flues and I deem it the best manner of arranging a coil-box for the purpose and consider it one of the salient points in the construction of the system.

In applying my system of heating and ventilating for use the flues are arranged substantially in the manner shown in the drawings—that is, a series of flues are employed and arranged side by side and built up together, forming what I call a "battery," and in the construction of these flues I prefer that

the dividing-walls between adjacent flues shall be common to such flues and that a portion of each heat-flue shall overlap a portion of a ventilating-flue and that such partition 5 shall be of a good heat-conducting medium, whereby heat from the heat-flue shall be conducted to the ventilating-flue to rarefy the air therein and cause the necessary draft.

The operation of the system as disclosed in 10 the drawings is very simple. The parts having been arranged in the manner shown in the drawings and steam having been passed through the coils in the coil-boxes and it is desired that heat shall be supplied to the various apartments in a building, the slides, as 15 S¹⁴ in Fig. 4, being drawn out to open the bottom of the coil-box, air from the room F will be admitted into the coil-boxes and will circulate between the coils therein and will 20 be heated, and the dampers, as S¹¹, (shown in Fig. 4,) being raised the heat will rise and pass up through the different heat-flues and will be discharged into the rooms to be heated. The necessary supply of fresh and pure air 25 may be derived, as I have shown in the drawings, from the attic of a building, which is open to admit of a free circulation of the air therethrough, and may be conducted to the fresh-air room by means of the trap-door 30 G², provided with the cord G³ and pulley G⁴, which will enable the trap-door to be raised or lowered at will; or the air may be admitted into the fresh-air room in any suitable manner—that is, it may be taken directly 35 through a lattice window opening into the room or through an ordinary duct opening out from the foundation or the wall. The supply of air entering the coil-boxes at the bottom portions thereof may be regulated so 40 as to admit much or little, as may be desired, by means of the slides, as S¹⁴, (shown in Fig. 4,) one of such slides being provided for each coil-box. The volume of hot air and the temperature thereof are designed to be 45 regulated by persons in the different rooms, and this regulation is accomplished through and by means of the dampers S¹¹ and the cords, as S¹², as shown in Fig. 4, one of which said cords is designed to be connected with one 50 of the dampers of the coil-boxes, and each cord for a particular room is connected with the damper of the coil-box which supplies the heat for said room. By lowering the damper down over the coils the supply of heat 55 may be entirely shut off, which will leave the opening S¹⁰ in the portion of the coil-box above the coils, which will admit cool or cold air into the heat-flue. Raising the damper to its maximum height will close the opening 60 S¹⁰ in the box, thus allowing the heat to pass freely up through the flue and from the coils at the temperature caused by the contact of the steam-coil, and by adjusting the dampers S¹¹ at intermediate points fresh and cold air 65 will be allowed to enter the coil-box through the opening S¹⁰ and mingle with the hot air from the coils to modify the temperature

thereof to obtain the desired degree of heat in the rooms.

The ventilation of the different rooms is 70 accomplished through and by means of the ventilating-flues, as has been previously stated, being arranged side by side with heat-flues and overlapping the same and having common partitions of a good heat-conducting medium, so that as the heat arises in the heat-flues and supplies the hot air for a given room radiation through the said partitions between the heat and vent flues will cause 75 heat to be conducted into the ventilating-flue, causing a rarefaction of the air therein, which will result in a strong upward draft leading to points without the building and also resulting in a strong draft from the rooms and opening into said flues, which will cause the 80 vitiated air therein to be abstracted therefrom—that is, a free and strong circulation of air will be maintained in the said room. The air in its complete circulation, starting from the outside of the building, enters the fresh-air room F, passes through these different coil-boxes and through the different heat-flues, and is discharged into the different rooms and passes out into the different ventilating-flues and from thence is conducted 85 to points without the building, thus making a complete and full circulation through the different rooms in the building and supplying a large quantity of pure and fresh air, which is kept in constant motion or movement within the compartments without the necessity of using auxiliary means for circulating fresh air for ventilation—as, for instance, the use of a fan—as my system arranged in this manner and operated as above 90 stated will supply a larger volume of air in a given length of time than any other means I have employed or have seen tested.

I do not wish to be confined to the exact construction and arrangement of the parts as 95 herein disclosed, but desire to include in my claim all equivalent means that may be employed for the same purpose.

Having thus fully described my invention, what I claim, and desire to secure by Letters 100 Patent, is—

1. The combination of the flues T S, separated by means of the sheet-metal partition T⁸, provided with the opening S⁶, therein the flue S, having the register-opening S² and provided below with the compartment S⁸, through which the heat is supplied from within or without, the flue T being provided for ventilation and provided with the register-opening T⁶, so that the heat rising through 110 the heat-flue S enters an adjacent room through the register S², circulates through the room, and the heated partition T⁸, causing the air in the ventilating-flue T to be heated, the air therein rising produces a draft 115 from the adjacent room through the register-opening T⁶, thus bearing out of the room air therein contained, and producing a perfect circulation and consequent perfect ventila-

tion, all substantially as described and set forth.

2. In a heating and ventilating system, the flues U, T, S separated by the thin partition 5 of some ready heat-conducting medium, flue S for heat-flue, U for vent, and flue T divided vertically at or near the floor-line and the part below the floor for heat and the part above the floor for vent, in combination with 10 two rooms one above the other into which the heated air is delivered from the heat-flues and from which the foul air passes into the vent-flues.

3. In a system for heating and ventilating, 15 the combination with the heat-flue S, of the compartment or box S⁸, provided with slide S¹⁴, and the trap-door S¹¹, for regulating the supply of heat to the heat-flue, all substantially as described and shown.

20 4. In a system for heating and ventilating, the combination with a heat-flue, of the compartment or box S⁸, provided with the slide S¹⁴, and the trap-door S¹¹, and the steam-coil contained within the said box or receptacle, 25 all substantially as described and shown.

5. In a system for heating and ventilating, the combination of the air-shaft G, provided at its top with the trap-door G², provided with

suitable means for raising and lowering the same, the hot-air room F', the compartment 30 or box S⁸, provided with slide S¹⁴, and the trap-door S¹¹, the heat-flues S' T' V' W', and the vent-flues T⁵, U, W⁴ and X separated by sheet-metal partitions, all substantially as described and shown. 35

6. In a system for heating and ventilating, the combination, with two compartments, arranged, one above the other, of three flues arranged side by side successively, and so that one outside flue will be for heat extending from below the first floor, up near the top of the second floor, the other outside flue for vent extending the full height of the two rooms and opening out at a point above, the intermediate flue divided horizontally by a 40 partition at or near the floor-line between the compartments, the lower part for heat and the upper part for vent, each of said flues or sections thereof having suitable communication with said compartments or one of them. 45

In testimony whereof I affix my signature in presence of two witnesses.

WILLIAM D. DICKSON.
